UNITED STATES PATENT OFFICE.

LOUIS WOJIDKOW, OF BROOKLYN, NEW YORK.

DESIGN FOR A KETTLE-STAND.

SPECIFICATION forming part of Design No. 25,474, dated May 12, 1896.

Application filed April 11, 1896. Serial No. 587,219. Term of patent 3½ years.

To all whom it may concern:

Be it known that I, LOUIS WOJIDKOW, a citizen of the United States, residing at Brooklyn, in the county of Kings and State of New York, have invented and produced a new and original Design for a Stand for Kettles, of which the following is a specification, reference being had to the accompanying drawing, which shows a perspective view of the same.

5 The leading feature of my design consists of a standard bifurcated and curved downwardly at its upper end and bifurcated and extended into a fanciful base at its lower end.

A is a standard bent over and bifurcated at its upper end, as shown at B, and ornamented, as shown at C. The lower end is also bifurcated and extended into a base D, consisting of fanciful scrolls, supporting thereon the tray E.

What I claim is—
The design for a kettle-stand substantially as herein shown and described.

LOUIS WOJIDKOW.
